LOOSE LEAF BINDER

Adolph G. Lotter, Milwaukee, Wis., assignor to
 Stationers Loose Leaf Company, Milwaukee,
 Wis., a corporation of Wisconsin

Application December 9, 1937, Serial No. 178,957

13 Claims. (Cl. 129—24)

This invention relates to binders and refers particularly to loose leaf binders of the large record book type.

Binders of this type generally comprise a back to which the covers are hingedly connected, and binder posts which pass through the body of leaves and are detachably connected either with the covers or the back. Generally, pintle bars slidably carried by the back or the covers with 5 pintles engageable in loops or openings in the ends of the binder posts are employed for detachably connecting the posts with the back and covers.

Disengagement of the pintle bars from the 15 binder posts is usually effected by a manually applied pull on the bar, whereas reengagement is preferably effected automatically upon closure of the cover. Several different schemes of automatically reengaging a pintle bar with the binder 20 posts have been proposed in the past, but these past expedients left room for improvement.

It is therefore an object of this invention to provide an improved manner of automatically reengaging the pintle bars with the binder posts 25 upon closure of the covers.

More specifically it is an object of this invention to provide means for automatically moving the pintle bars of a binder of the character described to their closed post engaging positions, 30 which is so designed that the entire mechanism is small and compact and so constructed as to require no change in design or construction of the binder.

Another object of this invention is to provide 35 means for automatically closing the pintle bar of a binder of the character described by positively moving the same by motion generated by the closure of the cover as distinguished from past constructions in which closure of the cover 40 merely released a spring which in turn actuated the pintle bar.

A further object of this invention is to mount 45 the motion generating elements by which the motion produced by closure of the cover is translated into sliding movement of the pintle bar, so that they are carried by and moved with the cover and are at all times in operative relation to the pintle bar so as to insure against the possibility of misalignment when the binder is open.

50 With the above and other objects in view which will appear as the description proceeds, this invention resides in the novel construction, combination and arrangement of parts substantially as hereinafter described, and more particularly defined by the appended claims, it being under-

stood that such changes in the precise embodiment of the herein disclosed invention may be made as come within the scope of the claims.

The accompanying drawings illustrate two complete examples of the physical embodiment of the invention constructed in accordance with the best modes so far devised for the practical application of the principles thereof, and in which:

Figure 1 is a plan view of a portion of a record book type loose leaf binder showing the same open with one cover thrown back, and with the binder back tipped rearwardly;

Figure 2 is an enlarged view of part of the binder, with the body of leaves and the lower cover viewed flatwise, and with the upper edge 35 of the back disengaged from the binder posts and the upper cover thrown back;

Figure 3 is a sectional view longitudinally through the back of the binder approximately on the plane of the line 3—3 in Figure 2, but 20 with the pintle bar closed and the cover in its closed position, parts being broken away and in section;

Figure 4 is a cross sectional view taken through Figure 1 on the plane of the line 4—4; 25

Figure 5 is a cross sectional view taken through Figure 2 on the plane of the line 5—5;

Figure 6 is a plan view similar to Figure 2, showing a slightly modified embodiment of the invention; 30

Figure 7 is a longitudinal sectional view through Figure 6 substantially on the plane of the line 7—7, but with the cover swung up to its closed position; and

Figure 8 is a perspective view of the component 35 parts of the pintle bar actuating mechanism shown separated.

Referring now particularly to the accompanying drawings in which like numerals indicate like parts throughout the several views, the numeral 40 5 designates the back of a binder of the character described, to which covers 6 are hingedly connected as at 7. The body of leaves 8 is held in place by a plurality of binder posts 9 detachably connected at their opposite ends to the back, in 45 a manner now about to be described.

Along each side edge of the back is a flat tube 10 in which a pintle bar 11 is slidably mounted. In line with each of the binder posts, the outer edges of the tubes 10 have openings 12 for the 50 reception of the adjacent ends of the binder posts, and likewise adjacent to each binder post, the pintle bars have their outer edges cut away as at 13 to accommodate the ends of the binder posts. Each pintle bar has the requisite number 55

of pintles 14 to pass through holes in the ends of the binder posts. Hence, attachment of the binder posts with the back is effected by sliding the pintle bars to their closed post engaging positions after the post ends have been properly engaged in the openings 12.

To facilitate manual actuation of the pintle bars to and from their closed positions, each has one end thereof projecting from the tube and 10 provided with a grip 15.

While the pintle bars may be manually moved to and from their closed binder post engaging positions, it is desirable to provide means for automatically moving them to closed positions 15 upon closure of the covers. For this purpose an automatic actuating mechanism designated generally by the letter A connects each pintle bar with its associated cover. These actuating mechanisms are duplicates. Consequently, a description 20 of one will suffice for both.

Each actuating mechanism comprises a pusher member 16 in the form of a block with pins 17 projecting from the opposite ends thereof. These pins are slidably received in the outer edge portion of the tube 10 in axial alignment with the 25 pintles 14 where they are held by the pintle bar engaging the block, as best shown in Figure 3.

The block of the pusher member 16 projects through an opening 18 in the outer edge of the 30 tube 10 and has a knuckle member 19 pivotally connected thereto by a hinge pin 20. A torsion spring 21 coiled about the pin 20 yieldingly urges the knuckle member into a position of alignment with the block-like pusher member 16, in which 35 position the spring propelled movement of the knuckle member is limited by the engagement of lugs 22 carried thereby with the side of the block 16.

Pivotedly connected to the knuckle member is a 40 lever 23. The outer end portion of this lever underlies a metal plate 24 which forms part of the hinge connection between the cover and the binder back and is slidably and pivotally connected with the plate by a pin 25 fixed to the plate 45 and engaging in a slot 26 in the outer end of the lever. The body of the cover is cut away as at 27 to accommodate the lever and permit the same to move in a manner to be described during opening and closing of the cover.

The plate 24 has an opening 28 to expose part 50 of the lever and accommodate the knuckle member 19 and that portion of the lever attached thereto. One edge 29 of this opening constitutes a fixed cover carried abutment which engages a roller 30 fixed to the lever to impart motion thereto during closure of the binder for the purpose of shifting the pusher member in a direction to slide the pintle bar to its closed post engaging position. It is to be observed that this 55 edge 29 of the opening 28 is inclined, the purpose of which will be hereinafter described.

It is also to be observed that the lever is at all 60 times in an inclined position with respect to a plane normal to the axis along which motion of the pusher member is constrained.

The manner in which closing movement of the cover imparts the necessary motion to the lever to effect the desired actuation of the pintle bar is best understood from reference to Figure 4.

As indicated in construction lines in this figure, 70 a fixed point on the cover and specifically any point on the edge 29 of the opening 28 swings in an arc a-b as the cover is closed. At the same time, the periphery of the roller 30 would describe a compound arc c-d-e if permitted. This

follows from the fact that the roller is carried by the lever 23 which swings first about the axis of the hinge pin 20 and then after alignment of the knuckle member 19 with the pusher member 16, swings about the axis of the pins 17.

However, the arc a-b crosses the compound arc c-d-e at the point X. At this point in the motion of the parts, the edge 29 of the opening 28 engages the periphery of the roller, and thereafter the roller is constrained to move along arc 10 a-b.

This arc, as clearly shown, constantly approaches the axis of the pins 17 which is also the axis along which the pusher member is constrained to move. The radial distance from this 15 fixed axis to the periphery of the roller thus decreases, and inasmuch as the lever 23 is inclined with relation to a plane normal to the said fixed axis of the pins 17, it follows that the pusher member is propelled laterally in a direction to 20 push the pintle bar to its closed post engaging position.

As represented by the illustration shown in construction lines in Figure 4, the differential in 25 the radial distance from the fixed axis of the pins 17 to the periphery of the roller 30 accelerates as the cover approaches its closed position. To offset this acceleration and restrict the developed lateral motion to the distance desired is the function of the inclination of the edge 29. 30

As shown, this inclination is such that as the 35 lever 23 is swung about its pivot 25 during closure of the cover, the fixed point on the cover represented by the then engagement of the roller periphery with the edge 29 moves continuously outwardly so that the resultant motion on the part of the pusher member is just sufficient to slide the pintle bar to its proper post engaging position.

From the description thus far, it will be seen 40 that the desired motion on the part of the pusher member during closure of the cover is produced primarily by the spaced relationship of the axis along which the pusher member is constrained to move and the axis of the hinge connection 45 between the cover and the back.

The torsion spring 21 which, as hereinbefore noted, tends to swing the knuckle member 19 into planar alignment with the block of the pusher member, is sufficiently strong to offset 50 the tendency of the lever 23 to push the pusher member about the axis of its pins 17 during closure of the cover and to insure translation of any motion imparted to the lever during the initial closing motion of the cover into proper sliding 55 movement of the pintle.

It is to be observed, however, that the point at which closing movement of the cover begins to take effect on the lever does not occur until 60 the cover has been swung to a position at which the knuckle member is almost in planar alignment with the block of the pusher member.

In the embodiment of the invention so far described the motion of the pusher member is imparted to the pintle bar by the engagement of one of its pins 17 with the back of one of the pintles. If desired, the motion of the pusher member may be transmitted to the pintle bar by having the block 16 of the pusher member engage a shoulder 35 on the pintle bar, as shown in 70 Figures 6 and 7. The manner of mounting the pusher member, however, is identical to that described.

In all other respects, with the possible exception 75 of the shape of the opening in the cover carried

plate 24 and the specific relationship of the lever 23 thereto, this form of the invention is like that previously described.

In practice, the back as well as the covers are 5 completely covered by a suitable binding which has been omitted in the drawings for the sake of clarity.

From the foregoing description taken in connection with the accompanying drawings, it will 10 be readily apparent to those skilled in the art, that this invention provides a smooth acting positively driven mechanism for closing the pintle bar of a record book type loose leaf binder, and that because of its permanent connection 15 between the cover actuated means and the pintle bar, misalignment and consequent difficulties during closure of the binder are precluded.

What I claim as my invention is:

1. In a binder of the character described including, a back, a cover hinged to the back, and binder posts adapted to pass through a body of leaves: means for detachably connecting the ends of the binder posts with the back including a pintle bar; means for actuating the pintle bar 25 to detach the binder post ends from the back; and means for actuating the pintle bar to closed post engaging position upon closure of the cover comprising, a lever slidably and pivotally connected with the cover; means for connecting the lever with the pintle bar and constraining the inner end of the lever to a sliding motion parallel to the sliding motion of the pintle bar; and means on the cover engageable with a part on the lever for effecting a sliding motion of said inner end 30 of the lever in a direction to close the pintle bar.

2. In a binder of the character described including, a back, a cover hinged thereto, and a binder post: means for detachably connecting the binder post with the back including a longitudinally slidably pintle bar; and means for sliding the pintle bar to its closed post engaging position upon closure of the cover comprising a pusher constrained to sliding motion and engageable with the pintle bar to move the same to its 45 closed post engaging position; and a lever connected with the pusher and the cover and operable by the cover during closing motion thereof to actuate the pusher.

3. In a binder of the character described including, a back, a cover hinged thereto, and a binder post: a pintle bar slidably carried by the back and having a pintle to pass through an opening in the end of the binder post for detachably connecting the binder post with the 50 back; the axis of said hinged connection between the cover and back and the axis of the pintle being spaced apart; and means for pushing the pintle bar to its closed position upon closure of the cover comprising, a linkage having one end constrained to a sliding motion parallel to the pintle axis and connected at said end with the pintle bar and having its other end engageable with an abutment on the cover, said abutment swinging in an arc which approaches the axis of 55 the pintle during closure of the cover so that the distance between the abutment and the axis of the pintle decreases, and said linkage being so positioned that its motion produced by the approach of the abutment towards the pintle axis 60 results in sliding motion of the pintle bar to closed position.

4. In a binder of the character described including, a back, a cover hinged thereto, and a binder post: a pintle bar slidably carried by the 75 back and having a pintle to pass through the

adjacent end of the binder post for detachably connecting the same with the back; a member constrained to move along an axis parallel to that of the pintle and engageable with the pintle bar to push the same to its closed position; a lever pivotally connected with said member; means slidably and pivotally mounting said lever on the cover; and an abutment on the cover engageable with a part on the lever during closure of the cover to move the lever in a direction to cause said pusher member to slide along its axis of motion to execute a pintle bar closing movement.

5. In a binder of the character described including, a back, a cover hinged thereto, and a binder post: a pintle bar slidably carried by the back and having a pintle to pass through one end of the binder post to detachably connect the same with the back; the axis of the hinge connection between the cover and back and the axis of the pintle being spaced apart so that a fixed point on the cover swings in an arc which approaches the axis of the pintle during closure of the cover; and means carried by the cover to move therewith at all times and having an operative connection with the pintle bar to utilize the decreasing distance between a fixed point on the cover and the pintle axis for effecting closing motion on the part of the pintle bar.

6. In a binder of the character described including, a back, a cover hinged thereto, and a binder post: a pintle bar slidably carried by the back and having a pintle to pass through one end of the binder post to detachably connect the same with the back; the axis of the hinge connection between the cover and back and the axis of the pintle being spaced apart so that a fixed point on the cover swings in an arc which approaches the axis of the pintle during closure of the cover; a pusher member constrained to move along the axis of the pintle and operable on the pintle bar to push the same to closed position; a fixed abutment on the cover; and a lever carried by the cover and connected with said pusher member engageable by said fixed abutment during its approach toward the axis of the pintle upon closure of the cover for moving the pusher member in a direction to close the pintle bar.

7. In a binder of the character described including, a back, a cover hinged thereto, and a binder post: a pintle bar slidably carried by the back and having a pintle to pass through one end of the binder post to detachably connect the same with the back; the axis of the hinge connection between the cover and back and the axis of the pintle being spaced apart so that a fixed point on the cover swings in an arc which approaches the axis of the pintle during closure of the cover; a member constrained to slide along the axis of the pintle and operable to push the pintle bar to its closed position; a plate carried by the cover having an opening therein, one edge of which forms a fixed abutment; a lever pivotally connected at one end with said pusher member and pivotally and slidably connected at its other end with the plate; and a part on the lever engageable by said fixed abutment so that during closure of the cover said lever is moved in a direction to cause the pusher member to close the pintle bar.

8. In a binder including a back, a cover hinged thereto, and a binder post: a pintle bar slidably carried by the back and detachably connected with the binder post when in a closed position;

- 5 a member constrained to move along an axis parallel to the sliding motion of the pintle bar and spaced from the axis of the hinge connection between the cover and back so that a fixed point on the cover swings in an arc which approaches said axis to which the motion of said member is constrained; a connection between said member and pintle bar whereby motion of said member in one direction closes the pintle bar; an abutment 10 on the cover; and a lever pivotally connected at one end with said member and engageable by said abutment on the cover at a distance from its pivotal connection with said member, said lever being inclined with respect to a line drawn along the shortest distance between said abutment and said fixed axis so that upon closure of the cover the lever is swung in a direction to actuate said member in a pintle bar closing motion.
- 15 9. In a loose leaf binder of the character described: a back; a cover hinged to the back; a binder post; a pintle bar slidably carried by the back and detachably connected with the binder post; a member constrained to move along a fixed axis parallel to the sliding motion of the pintle bar and operable upon motion in one direction 20 to push the pintle bar to a closed post engaging position; a plate carried by the cover having an opening therein, one edge of which forms an abutment, said fixed axis along which said member is constrained to move and the axis of the hinge connection between the cover and back being spaced apart and so related that the fixed 25 abutment on the cover swings in an arc which approaches said fixed axis during closure of the cover; and a member constrained to move in a plane parallel to said cover carried plate and connected with said first named member and engageable by the fixed abutment to move said first named member in a pintle bar closing motion 30 during closure of the cover by virtue of the approach of said fixed abutment toward said fixed axis during closure of the cover.
- 35 10. In a loose leaf binder of the character described: a back; a cover hinged to the back; a binder post; a pintle bar slidably carried by the back and detachably connected with the binder post; a member constrained to move along a fixed axis parallel to the sliding motion of the pintle bar and operable upon motion in one direction 40 to push the pintle bar to a closed post engaging position; a plate carried by the cover having an opening therein, one edge of which forms an abutment, said fixed axis along which said member is constrained to move and the axis of the hinge connection between the cover and back being spaced apart and so related that the fixed 45 abutment on the cover swings in an arc which approaches said fixed axis during closure of the cover.
- 50 55

cover; a lever pivotally connected at one end with said member and having its other end portion lying flat against the cover carried plate; means pivotally and slidably connecting said other end portion of the lever with the cover carried plate and holding the lever in an inclined position so that motion of the lever resulting from a force acting thereon in a plane normal to said fixed axis is translated into sliding motion of said member along said fixed axis; and means on the lever engageable with the fixed cover carried abutment to apply such force to the lever during closure of the cover.

5 10 11. In a loose leaf binder of the character described: a back member; a cover member hinged to the back member; a binder post; a pintle bar slidably carried by the back member and engageable with the binder post for detachably connecting the binder post with the hingedly connected members; a lever carried by the cover member; means for connecting the lever with the pintle bar and constraining the inner end of the lever to a sliding motion parallel with the sliding motion of the pintle bar; and means on the cover member engageable with a part on the lever for 15 20 25 effecting sliding motion of the inner end of the lever in a direction to move the pintle bar into post engaging position.

12. In a loose leaf binder of the character described: a back member; a cover member hinged to the back member; a plurality of posts; a pintle bar carried by one of said members and slidably to and from engagement with said posts; an actuator movably mounted on said member which carries the pintle bar and operable to slide the 30 35 40 pintle bar into post engaging position; and co-operating elements carried by said back member and cover member for moving the actuator during closure of the cover to slide the pintle bar into post engaging position.

13. In a loose leaf binder of the character described: a back member; a cover member hinged to the back member; a binder post; a pintle bar slidably carried by one of said members and engageable with the binder post for detachably connecting the binder post with the hingedly connected members; a lever connected with the cover member; means for connecting the lever with the pintle bar so that sliding motion may be imparted to the pintle bar by the lever; and means on the cover member engageable with a part on the lever for effecting motion of the lever in a direction necessary to slide the pintle bar into post engaging position as the cover member is swung toward closed position on its hinged connection with the back member.

55 45 50 55 ADOLPH G. LOTTER.
